ATTORNEY.

UNITED STATES PATENT OFFICE

2,222,002

GUARD OR SHIELD FOR HANDLES OF PICKS

Houston P. Sewell, Montgomery, Ala.

Application January 24, 1940, Serial No. 315,304

1 Claim. (Cl. 306—37)

This invention relates to guards or shields for the handles of picks, with particular reference to miners' picks, though of course the invention may be used upon pick handles generally.

5 In mining coal or quarrying rock, particles of coal or rock fly up against the under side of the handle immediately back of the metal pick, and this continual bombardment ultimately wears and weakens the handle at this point, until it 10 finally breaks off.

It is the prime object of the present invention to provide a guard of elastic material such as tough or partially vulcanized, or reinforced rubber, in the form of a sleeve having an opening 15 slightly less than the measure of the handle at the pick head, and which sleeve or guard may be slid in place over the handle, up against the pick head and there frictionally held by virtue of its slight elasticity, and thus protect the 20 handle from the wearing action of flying particles.

Another object is to provide a handle guard of toughened rubber in the form of a sleeve for fitting over a pick handle or the like, at 25 the tool head, the said guard being formed with relatively thin side walls for affording the requisite elasticity for stretching and fitting the device upon the handle and frictionally holding it in place, and with relatively thickened and 30 laterally protruded bottom and top portions for affording the required wear and endurance to the device.

With these objects in view attention is directed 35 to the drawing, which shows a preferred embodiment of the invention, and wherein:

Figure 1 is a side elevation of a pick showing a guard in accordance with my invention mounted on the handle, next to the pick head.

Figure 2 is a perspective view of the guard 40 alone, on a greatly enlarged scale.

Figure 3 is an enlarged fragmentary side elevation of the pick showing a longitudinal section through the guard mounted on the handle of the pick.

45 The invention is for use upon a standard pick A having the wooden handle B and metal pick

head C, and comprises a sleeve-like guard referred to generally at 5.

This guard is made of any suitable, slightly elastic material such as synthetic rubber, or partially vulcanized rubber, or rubber suitably 5 reinforced with cord or fabric after the manner of automobile tires.

The guard 5 is formed in the shape of a sort of sleeve with spaced and relatively thin sides or gores 6 for providing sufficient resiliency, 10 integrally joined at top and bottom to relatively thick and heavy portions or soles 7 and 8 for the sake of endurance under use and wear, the aperture 9 of the guard being slightly less than the measure of the handle B upon which it is to be 15 fitted, so as to be frictionally retained thereon after installation.

The soles 7 and 8 are, if necessary, tapered outwardly from the pick head, as shown, at 7a, 8a, so as to fit snugly over the tapered shank B1 of 20 the handle, next the head C. The soles are also protruded or flanged laterally beyond or over the gores 6, as shown at 7b, 8b, for providing protecting flanges or deflectors for the gores 6. These flanges prevent flying particles from striking 25 and destroying the weaker gores 6.

From the foregoing description, the construction and use of the device will be fully understood. The guard formed as stated, is fitted 30 tightly upon the handle up against the pick head, with the soles disposed at top and bottom of the handle, to which it is frictionally held by its own resiliency.

While I have here described a certain embodiment of the invention, the features thereof may 35 be varied within the scope of the claim.

I claim:

A sleeve-like guard for mounting upon a tool handle at the head of the tool, the guard having relatively thin and resilient sides for frictionally 40 gripping the handle, and relatively thick and wear resistant top and bottom portions, said top and bottom portions being flanged laterally as protections for the sides.

45

HOUSTON P. SEWELL.
